UNITED STATES PATENT OFFICE.

GABRIEL UPTON, OF PHILADELPHIA, PENNSYLVANIA, ASSIGNOR TO CONYERS BUTTON AND THEODORE A. FLEU, OF SAME PLACE.

DESIGN FOR KNITTED FABRIC AND FRINGE.

Specification forming part of Design No. **11,274**, dated July 1, 1879; application filed May 31, 1879.
[Term of patent 3½ years.]

To all whom it may concern:

Be it known that I, GABRIEL UPTON, of Philadelphia, Pennsylvania, have produced or invented a new and original Design for a Knitted Fabric and Fringe, of which the following is a specification.

My design for a knitted fabric and fringe is fully shown in the accompanying photographic illustration.

The body of the fabric consists of vertical cords *a*, lateral threads *b*, and short projecting plumes *d*, carried by said cords *a* and threads *b*. The fringe consists of loose pendent cords *f*, carrying short projecting plumes *i*.

Irrespective of the colors employed, I claim—

1. The design for a knitted fabric, said de-

sign comprising the cords *a*, threads *b*, plumes *d*, loose pendent cords *f*, and projecting plumes *i*, all substantially as described, and as shown in and by the accompanying photographic illustration.

2. The design for a knitted fringe, said design comprising the loose pendent cords *f*, with projecting plumes *i*, all substantially as described, and as shown in and by the accompanying photographic illustration.

In testimony whereof I have signed my name to this specification in the presence of two subscribing witnesses.

GABRIEL UPTON.
